ABSTRACT

A method of preserving cosmetics by admixing with the cosmetic formulation a microbiocidally effective amount of 1-aminoethyl-2-naphthyl imidazoline, having the structure:

wherein R is the residue of a naphthalene-carboxylic acid as a microbiocidal preservative agent.

5 Claims, No Drawings

MICROBIOCIDAL NAPHTHENYL IMIDAZOLINES

This is a continuation-in-part of co-pending application Ser. No. 883,641, filed Dec. 9, 1969, now issued as U.S. Pat. No. 3,705,027, dated Dec. 5, 1972.

This invention relates to the microbiocidal use of 1-aminoethyl-2-naphthyl imidazoline, having the structure:

wherein R is the residue of a naphthene-carboxylic acid.

It has been discovered that the above-naphthyl imidazolines have a high order of microbiocidal effectiveness which is greatly superior to other imidazolines having different acid residues.

They are especially utilizable to preserve cosmetics so as to prevent phase separation, discoloration and other effects of microbial proliferation, including that of pathogenic strains of microorganisms which may cause serious or minor infection of the skin or mucosa.

Naphthenic acids are well-known to the art and are available commercially, primarily as the result of various extractive procedures carried out in refining naturally occurring petroleums and petroleum fractions, particularly gas-oil distillates boiling in the range of 400°-700°F. Naphthenic acids are found particularly in petroleums originating in the western part of the United States, especially in California; in the northern part of South America, especially Venezuela, Colombia and Aruba; in the southern part of Europe, especially Rumania, and, to a lesser extent, in crude oils originating in Louisiana, along the Texas gulf coast, in Peru, Mexico, Poland, the Soviet Union and Germany.

The chemical nature of these naphthenic acids is more or less ill-defined, but they all have in common the characteristic of possessing alicyclic nuclei. These may be five or six membered carbon atom ring systems, various condensed ring systems, and other related materials as disclosed in Fieser, "Organic Chemistry," 3rd ed. 1956, pages 97-98.

EXAMPLE 1

2,324 grams (or 9.28 mols) of Enjay's Refined Naphthenic Acid having an acid number of 224, and 1,265 grams (or 12.07 mols) of diethylene triamine were charged into an agitated flask fitted with a packed fractionating column system for the purpose of separating and removing water formed in the reaction and returning stripped amine to the reactor. Aquametric titration of the charged amine indicated a water content of 1.17%.

The mixture was agitated and heated under reduced pressure at about 150°C. pot temperature and at 216 mm pressure, gradually raising the pot temperature to about 200°C. during a period of about 12 hours. The water of reaction distilled along with some of the diethylene triamine, through the fractionating column, which stripped off the water and returned the amine to the reactor. When no more water distilled, the excess amine was distilled off at about 5 mm pressure and 190°C.

The total amount of water collected was 321 grams; correcting for the initial water content, 17 mols of water was obtained, or 91.5% of the theoretical amount for the formation of the imidazoline.

A weighed sample was titrated potentiometrically to the first break with HCl in alcohol, indicating 87.4% activity. After reacting the non-tertiary nitrogen with phenyl isothiocyanate, titration with perchloric acid indicated 95.2% reaction.

10 The product was found to be effective against aerobic bacteria at from 25 to 150 parts per million at 37°C. during 4 hours.

EXAMPLE 2

15 The product was assayed bacteriologically by the Standard Broth Dilution Test Method. Aliquots of a solution of the aminoethyl naphthyl imidazoline were added to appropriate broth culture media contained in test tubes, so that various concentrations were obtained. The tubes so prepared were inoculated with 24 hour broth cultures of the test bacteria, or 14 day aqueous spore suspensions of the test fungi, or 7 day broth cultures of the algae. The inoculated tubes were incubated as follows: bacteria for 72 hours at 37°C.; fungi for 14 days at 28°C.; algae for 7 days at 25°C. Following the aforementioned incubation periods the tubes were examined for the presence or absence of macroscopic growth. The lowest concentration of test material not permitting macroscopic growth is designated as the Minimum Inhibitory Level.

20 The test organisms employed were: *Escherichia coli* = E.c.; *Pseudomonas aeruginosa* = ps.a.; *Staphylococcus aureus* = S.a.; *Streptococcus faecalis* = S.f.; *Aspergillus niger* = A.n.; *Penicillium expansum* = P.e.; and *Chlorella pyrenoidosa* = C.p.

Table 1

Parts per million of 1-aminoethyl-2-naphthyl imidazoline						
Gram Negative E.c.	Gram Positive Ps.a.	Gram Positive S.a.	Fungi S.f.	Fungi A.n.	Fungi P.e.	Algae C.p.
10	250	10	10	500	500	10

EXAMPLE 3

45 AT 0.5% of 1-aminoethyl-2-naphthyl imidazoline as a component of face creams and lotions, microbial growth on storage was found to be negligible. In the case of other cosmetic preparations, such as baby lotions, hair-set preparations, powders, shampoos, and the like, preservation action was excellent in the range of 0.1% to 2% by weight.

50 55 This compound may be employed either as the free amine or as its salts of inorganic or organic acids. Such acids may include, for example, hydrochloric, sulfuric, phosphoric, acetic, lauric, oleic, gluconic, oxalic, tauric, citric, benzoic and substituted benzoic, paratoluene sulfonic, sulfamic, and the like.

EXAMPLE 4

Non-ionic Baby Lotion

Component	Parts by Weight
Mineral oil (65/75 S.S.U. at 100°F)	35.0
Lanolin, anhydrous	1.0

-Continued

Component	Parts by Weight
Cetyl alcohol	1.0
Atlas Chemical Ind. "Tween 80" (polyoxyethylene sorbitan monooleate)	5.4
Atlas Chemical Ind. "Span 80" (sorbitan monooleate)	2.6
Naphthalenyl imidazoline	0.5
Distilled Water	O.S. to make 100.0

Here, and in the succeeding examples, "naphthalenyl imidazoline" or more simply, "imidazoline" will be understood to represent the 1-aminoethyl-2-naphthalenyl imidazoline of the invention. Although the free amine is named, as readily soluble in the oily it may also be employed in an aqueous phase as one of its salts.

The oil, lanolin, cetyl alcohol, Tween and Span were combined and mixed and heated to 60°C. The water was heated to 62°C and slowly added to the mix with propeller agitation. The resulting emulsion was allowed to cool to room temperature under agitation. The product had a pH of about 7.0.

EXAMPLE 5

Cold Cream

Component	Parts by Weight
Mineral oil (65/75 S.S.U. at 100°F)	50.0
Beeswax, U.S.P., white, sunbleached	7.0
"Tween 40" (polyoxyethylene sorbitan monopalmitate)	2.0
Atlas Co.'s "G-1726" (polyoxyethylene sorbitol beeswax derivative)	8.0
"Naphthalenyl imidazoline"	0.5
Distilled water,	O.S. to make 100.0

The mineral oil, beeswax, imidazoline and the surfactants were combined and heated under agitation to 70°C; the water was heated to 72°C, and then added slowly, with propeller agitation, to the oily phase.

The cream was allowed to cool with adequate agitation to the set-point, and poured into jars.

The pH was in the range of about 6.5 to 7.0.

EXAMPLE 6

Shampoo

Component	Parts by Weight
Onyx Chemical Co.'s "Maprofix 563" (99% active sodium lauryl sulfate)	12.0
Onyx Chemical Co.'s "Super Amide L-9C" (methyl laurate-diethanolamine condensate 97% paste)	3.0
Naphthalenyl imidazoline	0.5
Distilled water	O.S. to make 100.0

Heat the water to 50°C. Slowly add the Maprofix while agitating, until it is completely dissolved. Add the Super Amide, previously melted and the imidazoline. Agitate until clear, while cooling.

Adjust the pH to 7.0.

EXAMPLE 7

Creme Rinse

Component	Parts by Weight
Onyx Chemical Co.'s "Ammonyx 4" (25% active)	7.5
Cetyl alcohol	0.3
Potassium chloride	0.75
Imidazoline	0.5
Distilled water	O.S. to make 100.0

The Ammonyx, cetyl alcohol, "imidazoline," and 90% of the water are heated together to 65-70°C. The potassium chloride is dissolved in the balance of the water, heated to 70-75°C, and added to the mix. The whole is agitated while cooling to room temperature.

Adjust the pH to 5.0.

EXAMPLE 8

Body Lotion

Component	Parts by Weight
Amerchol Cholesterol Products, Inc. "Amerchol L-10"	5.0
Amerchol's "Acetulan"	2.0
Triple-pressed stearic acid	5.0
Glyceryl monostearate	1.0
Propylene glycol	5.0
Triethanolamine	1.0
Imidazoline	0.5
Distilled water	O. S. to make 100.0

The first four components and the "imidazoline" are combined and are heated together to 85°C. The mixed water, propylene glycol and triethanolamine are separately heated to 85°C and added slowly to the oily phase while mixing. The agitation is continued while cooling to room temperature.

The pH of the product is about 8.0.

The invention claimed is:

1. A method of inhibiting the growth of bacteria or fungi in creams, lotions and shampoos subject to such growth which comprises applying to said bacteria or fungi an amount sufficient to inhibit their growth of the compound 1-aminoethyl-2-naphthalenyl imidazoline or a salt thereof selected from the group consisting of the hydrochloric, sulfuric, phosphoric, acetic, lauric, oleic, gluconic, oxalic, tartaric, citric, benzoic, paratoluene, sulfonic and sulfamic acid salts.

2. The method of claim 1 wherein the cosmetic is a lotion.

3. The method of claim 2 wherein the cosmetic is a cold cream.

4. The method of claim 1 wherein the cosmetic is a shampoo.

5. The method of claim 1 wherein the cosmetic is a creme rinse.
